UNITED STATES PATENT OFFICE.

EDGAR M. BENHAM, OF NORWOOD, AND CHARLES M. HIRN, OF MADISONVILLE, OHIO,
ASSIGNORS TO THE MOSLER LOCK COMPANY, OF COVINGTON, KENTUCKY, A COR-
PORATION OF OHIO.

LOCK.

Application filed August 5, 1924. Serial No. 730,134.

To all whom it may concern:

Be it known that we, EDGAR M. BENHAM and CHARLES M. HIRN, both citizens of the United States, residing, respectively, at Norwood, in the county of Hamilton and State of Ohio, and at Madisonville, in the county of Hamilton and State of Ohio, have invented certain new and useful Improvements in Locks, of which the following is a specification.

This invention relates to locks and more particularly relates to locks which require the manipulation of two keys to unlock the same, and which may be adjusted for different keys without replacing or altering the shape of the tumblers.

In an application for improvements in locks filed by Edgar M. Benham July 11, 1921, Serial No. 483,674, and now Patent No. 1,522,572, dated Jan. 13, 1925, there is disclosed a lock having two sets of alternately overlapping tumblers commonly pivoted, one set being master tumblers operable by a locking and unlocking key from one key tube of the lock, and the other set of tumblers being guard tumblers operable by a guard key from another key tube. Both sets of tumblers dog a stump on the bolt bar directly by means of recessed noses on the tumblers. A lock of such construction cannot be conditioned for other keys without substituting one or more new tumblers having their front recesses located differently from the recesses of the removed tumblers.

In an application filed by Edgar M. Benham April 26, 1922, for improvements in changeable combination key locks, Serial No. 556,709, now Patent No. 1,522,573, dated Jan. 13, 1925, there is shown a lock construction having similar tumbler arrangement but instead of the tumblers directly dogging a stump on the bolt plate the tumblers, or some of them, are arranged to dog finger plates which are adjustably mounted on the bolt plate, so that by adjusting these finger plates relatively to each other and to the bolt plate, the lock may be conditioned for different keys without disturbing the tumbler arrangement.

The principal object of this invention is to improve upon said constructions by providing a lock which is readily and easily changeable for different keys without requiring substitution of tumblers and at the

same time eliminates the adjustable finger plates, or the like. A further object of this invention is to provide a lock of the character described, and one which is simple, durable, sturdy and compact in construction. Other objects of this invention will be in part obvious and in part pointed out hereinafter.

In accordance with this invention, the previous construction is retained comprising two separate sets of tumblers nested together in alternate overlapping relation, and both sets have recessed noses arranged to dog a stump on the bolt plate directly. One set of tumblers are master tumblers having a plurality of perforations adjacent their rear edges and are adapted to be pivoted at any one of these perforations on a removable pin, carried by the casing, thus permitting this pivot point of each tumbler to be varied independently of the other tumblers. The tumblers may be conditioned for operation by different keys by varying their points of pivotal engagement with the pin, and to this end means are provided for permitting the perforated rear ends of these tumblers to be adjusted relatively to each other and to the lock casing by means of a new key, when the pin is removed, so that by engaging the pin with the tumbler perforations in their new alignment these tumblers are conditioned for the new key without requiring these tumblers to be removed from the lock or requiring the lock to be taken apart. If desired in addition to these master tumblers, there may be provided a set of guard tumblers. These guard tumblers may be similar in design and in manner of operation to the guard tumblers disclosed in said previous application Serial No. 483,674.

In order that a clearer understanding of this invention may be had, attention is hereby directed to the accompanying drawings forming a part of this application and illustrating one possible embodiment of this invention. Referring to the drawings, Fig. 1 is a top elevation of a lock embodying this invention, the lock being in unlocked condition; Fig. 2 is a bottom elevation of the same; Fig. 3 is a top elevation of the lock mechanism with the cover plate removed, showing the mechanism in unlocked position, this view being a sectional view taken on the line 3-3 of Fig. 7; Fig. 4 is a view

similar to Fig. 3 showing the new key in place and the master tumblers ready to be engaged in their new position by the removable pin; Fig. 5 is an elevation of the 5 interior of the lock with the tumblers removed, showing how the change key prevents full retraction of the bolt; Fig. 6 is a side elevation of a guard tumbler separately; Fig. 7 is a sectional view of the lock and is 10 taken on the line 7—7 of Fig. 4 with the change key in place; Fig. 8 is a sectional view taken on the line 8—8 of Fig. 1, also showing the change key in place; and Fig. 9 is a sectional view taken on the line 9—9 of 15 Fig. 1, but with the change key in place. Similar reference characters refer to similar parts throughout the several views of the drawings.

Referring to the drawings, we provide a 20 suitable casing for the lock mechanism, the casing comprising a box portion 1 and a cover plate or lid 2. The lid is provided with two suitable extensions or noses 3 and 4. The nose 3 rotatably steadies a key tube 25 5 for any regular key 6, and the nose 4 rotatably steadies a key tube 7 for a guard key 8. Inside the box, on its bottom, there is a 30 slidable bolt plate 9 which has a bolt portion 10 protruding through a suitable perforation in the front end of the box 1. Bolt plate 9 has a slot 11 through which extends a post 12 which is secured to the bottom of the box 1 and whereby the rear of the bolt plate 9 is guided. Bolt plate 35 9 carries towards its front a stump 13 which, when the lock is fully locked, is dogged by a set of master tumblers 14 and a set of guard tumblers 15. The guard tumblers 15 are fixedly pivoted on the post 12 and have 40 noses 16 at their front ends recessed, as at 17, and also have tails 18 at their rear ends adapted to be engaged by the guard key 8 when operated in key tube 7, whereby these tumblers may be set up so that the 45 recesses 17 are aligned with each other and with the stump 13 of the bolt plate 9. The master tumblers 14 have slots 19 through which the post 12 extends, whereby forward and rearward displacement is prevented, 50 but permitting the tumblers to pivot from their front and rear ends. These tumblers at their front ends have noses 20 recessed, as at 21, and are pivoted at their rear ends on a pin 22 which is removably positioned 55 through and in the bottom of the box 1, and which extends through any one of a series of perforations 23 provided in the rear ends of the tumblers 14, depending on the position of these tumblers relative to 60 each other and to the pin. Screw 22 has a head 24 exposed on the outside of the bottom of the lock and has a screw threaded portion 25 adjacent the head which is adapted to removably engage in a threaded perforation 65 provided therefor in the bottom of the

box 1. These master tumblers 14 when engaged by pin 22, which is the normal condition, are adapted to be set up by means of the regular key 6 operating in the key tube 5 to align their recesses 21 at their 70 front ends with each other and with the stump 13 on the bolt plate 9 to permit the stump 13 to move into these recesses, provided the guard tumblers have also been set up. The regular key 6 is adapted to retract the bolt plate 9 when the tumblers have been set up by turning the usual cam member 26 which engages a shoulder 27 provided in the bolt plate 9. Upon reverse 75 rotation of the regular key, cam member 26 80 engages shoulder 28 on the bolt plate 9 to project the bolt and to remove the stump 13 from the tumbler recesses. The master tumblers may be provided with shoulders 33 at their front edges which rest upon the stump 85 13 when the bolt is in locked position.

The master tumblers of this lock may be adjusted for any one of a very great number of different regular keys in the following manner:—There is a special key 29, 90 known as a change key, which is adapted to be inserted through a key hole 30 provided therefor in the bottom of the box 1. However, the upper corners 15' of the guard 95 tumbler noses, when the guard tumblers 15 are not set up, extend across the key way and prevent the insertion of the change key into the lock, but when the guard tumblers have been set up, these upper edges are removed from this key way, and the change 100 key may be inserted. When the change key 29 has been inserted through the key hole 30, it presents bits 31 over the top edges of the master tumblers 14, as at 32. The screw 22 is now removed from the lock with the 105 result that the rear ends of the tumblers fall to the lower side of the casing due to the action of the tumbler springs 34. The new key 6' is now inserted in the key tube 5 and turned in unlocking direction. This 110 movement of the new key first raises the front ends of the tumblers 14 against the change key to bring their recesses in alignment with stump 13, the bits of the change 115 key being fashioned accordingly, and then pivots the master tumblers about their front portions which are pressed upwardly against the change key 29, to move the perforations 23 at the rear of these tumblers 120 relatively to each other and to the casing into positions corresponding with the particular shape of the bits of the new key. Thus it will be apparent that the tumblers pivot on the change key 29 as they are being adjusted into their new positions. When 125 these tumblers have been so adjusted relatively to each other and to the casing by means of the new key, the pin 22 is replaced, and it will be found that the lock has 130 been adjusted for opening by means of the

new key and will no longer respond to the former key if the bits of the two keys differ. As a final operation, the new key is placed in locking position and the guard key 5 turned to set up the guard tumblers, and the change key 29 is removed. The change key cannot be removed from the slot 30 when the guard tumblers are not set up, nor can the change key be removed when 10 the master tumblers are set up due to the engagement of these tumblers intermediate some of the bits of the change key.

The bolt plate 9 is provided with a projection 35 which moves across the key way 30 when this plate is fully retracted. When the change key is in place, this projection strikes against a bit portion of the key 29 to limit movement and to prevent full retraction, thereby preventing unlocking of 20 the lock while the change key is in place. This is a safety feature preventing unauthorized unlocking of the lock.

It will thus be apparent that in a lock of the above described construction the 25 master tumblers may be adjusted relatively to each other and relative to a point of pivotal support to condition these tumblers for any one of a very great number of different keys. The lock may also be conditioned for other regular keys by substituting one or more tumblers having their front recesses located at different places in their noses, or their key engaging body portions cut to different shape. The lock may 30 also be conditioned for any one of a number of different guard keys by substituting one or more other guard tumblers having front recesses placed differently from the recesses of the removed guard tumblers.

40 As many changes could be made in the above construction, and many apparently widely different embodiments of this invention could be made without departing from the scope thereof, it is intended that all matter contained in the above description or 45 shown in the accompanying drawings shall be interpreted as illustrative and not in a limiting sense.

What we claim is:—

50 1. In a lock of the character described, in combination, a casing, a bolt plate, two sets of tumblers nested together in alternately overlapping relation and coacting with said bolt plate, a removable pivot carried at a fixed point in said casing and engageable with the tumblers of one set at their rear ends, means for adjusting the rear ends of said tumblers relatively to each other and relatively to said fixed point, said 55 pivot being replaceable to engage and hold the rear ends of said tumblers in their adjusted position for pivoting on said pivot, said means comprising a pivot for the front ends of said tumblers and movable independently of the bolt plate into and out of

engagement with the tumblers, and a key for moving said tumblers on said front pivot.

2. In a lock of the character described, in combination, a casing, a bolt plate, two sets of tumblers nested together in alternately overlapping relation and coacting with the bolt plate, a removable pivot carried at a fixed point in said casing and engageable with the tumblers of one set at 70 their rear ends, means for adjusting the rear ends of said tumblers relatively to each other and relatively to said fixed point, said pivot being replaceable to engage and hold the rear ends of said tumblers in their adjusted position for pivoting on said pivot, said means comprising a pivot for the front ends of said tumblers, said pivot being separate from the bolt plate and removable from the lock, and a key for moving said 75 tumblers on said front pivot.

3. In a lock of the character described, in combination, a casing, two sets of tumblers nested together in alternately overlapping relation, a removable pivot carried at 80 a fixed point in said casing and engageable with the tumblers of one set at their rear ends, means for adjusting the rear ends of said tumblers relatively to each other and relatively to said fixed point, said pivot being replaceable to engage and hold the rear ends of said tumblers in their adjusted position for pivoting on said pivot, said means comprising a key insertible through the bottom of the lock casing and having bits 85 disposable over the top edges of said tumblers toward the front and constituting a pivot for said tumblers, and another key for moving the tumblers against said key bits and pivoting said tumblers thereon.

4. In a lock of the character described, in combination, a bolt plate, a tumbler coacting with the bolt plate, a rear pivot adapted to engage the tumbler releasably and selectively at different points, a front pivot movable independently of the bolt plate and adapted to engage the tumbler at another point, said tumbler when engaging the front pivot being movable to place different points in 100 position for engagement by the rear pivot.

5. In a lock of the character described, in combination, a bolt plate, a tumbler coacting with the bolt plate, a rear pivot adapted to engage the tumbler releasably and selectively at different points, a front pivot movable independently of the bolt plate and adapted to engage the tumbler at another point, said tumbler when engaging the front pivot being movable to place different points in 105 position for engagement by the rear pivot, and a key for moving said tumbler on its front pivot.

6. In a lock of the character described, in combination, a casing, a bolt plate, a tumbler coacting with the bolt plate, a rear pivot 110

removably carried on the casing adapted to engage the tumbler releasably and selectively at different points, and a front pivot movable independently of the bolt plate and adapted to engage the tumbler at another point, said tumbler when engaging said front pivot being movable to place different points in position for engagement by said rear pivot when replaced on the casing.

7. In a lock of the character described, in combination, a bolt plate, a tumbler coacting with the bolt plate, a rear pivot adapted to engage the tumbler releasably and selectively at different points, a front pivot movable independently of the bolt plate and adapted to engage the tumbler at another point, said tumbler when engaging the front pivot being movable to place different points in position for engagement by the rear pivot, a casing, said front pivot comprising a key insertable through the bottom of the casing and having bits disposable over the top edge of said tumbler toward the front, and another key for moving the tumbler against key bits and pivoting said tumbler thereon.

8. In a lock of the character described, in

combination, a casing, a bolt plate having a stump, a tumbler having at its front a recessed nose abutting said stump, controlling movement of said bolt plate, a series of perforations in the tumbler adjacent its rear end, a removable rear pivot selectively engageable with said tumbler at any one of said perforations in accordance with the relative position of the rear end of the tumbler with respect to the casing, a key for pivoting said tumbler about said pivot to align said front recess with said stump, a change key insertible into said casing and having a bit disposable over the top edge of said tumbler toward its front and constituting a front pivot for said tumbler when said rear pivot is removed, a projection on said bolt plate, and said change key, when so positioned, being in the path of movement of said projection to prevent retraction of said bolt plate into fully retracted position and the unlocking of the lock, until said change key is removed.

This specification signed this 28th day of July, 1924.

EDGAR M. BENHAM.
CHARLES M. HIRN.
